UNITED STATES PATENT OFFICE.

THOMAS DE LA MARE, OF TOOKE, UTAH.

CONDUIT MOLD.

Application filed September 20, 1920. Serial No. 411,642.

To all whom it may concern:

Be it known that I, THOMAS DE LA MARE, a citizen of the United States, residing at Tooele, in the county of Tooele and State of Utah, have invented a new and useful Conduit Mold, of which the following is a specification.

The present invention relates to apparatus for molding a continuous pipe or conduit within a trench.

An object of the invention is to effect improvements in that conduit mold patented by me November 24, 1914, No. 1,118,558.

15 A more specific object is to provide means whereby a single conduit mold may be used to make conduits of at least two different sizes.

Another object is to provide improved 20 means for expanding and contracting the shell or drum of the apparatus.

A further object is to provide means for forming a bell or enlarged joint between adjoining sections of the conduit.

25 Other objects are to provide a conduit mold whose parts are readily detachable, making it easy to ship, and which are easily assembled in the field.

Still another object is to provide means 30 for keeping the concrete from getting under the cap, for preventing sticking of the concrete to the cap and drum, and for making a good surface on the inside of the conduit on the upper part thereof.

35 The invention will be best understood from a consideration of the following detailed description taken in connection with the accompanying drawing forming part of this specification, with the understanding, 40 however, that the invention is not confined to any strict conformity with the showing in the drawing, but may be changed and modified so long as such changes and modifications mark no material departure from the salient features of the invention as expressed in the appended claims.

In the drawing:

45 Figs. 1 and 1^a taken together show a vertical longitudinal sectional view of the improved apparatus in use with the shell or drum shown expanded.

Fig. 2 is a view partly in section and

partly in plan of that portion of the conduit and apparatus disclosed in Fig. 1.

Fig. 3 is an end elevation of the conduit 55 and mold, the view being taken from the enlarged or working end.

Fig. 4 is a vertical transverse cross-section.

Fig. 5 is a detail showing the arms 60 connected with a reversed block on the pull rod so that the mold may be used to make a smaller conduit.

The main body of the conduit mold is formed from a pair of arcuate shells 6, 65 each less than a semi-circumference and each having inturned flanges 7 along their upper edges, which flanges are always maintained spaced apart as indicated particularly in Figs. 3 and 4. The other edges of 70 the shells 6 have inturned flanges 8 narrower than the flanges 7. An auxiliary section 9 is employed which is arcuate and of the same curvature as the sections 6, when the mold is to be used for the largest size 75 of pipe for which it is designed. The auxiliary section 9 has its longitudinal edges terminating in inturned flanges 10 corresponding to the flanges 8. When the auxiliary section 9 is used with the shell sections 6, the flanges 8 and 10 will be abutted and joined by bolts or similar elements. When the apparatus is employed for making a smaller size of pipe, the auxiliary section 80 85 9 will be removed and the two flanges 8 will be joined together by bolts or the like.

Whether the particular shell is used for making relatively small or large sizes of pipe or conduit, it will be closed except on its upper side where the flanges 7 are normally spaced apart a short distance. The space between the flanges 7 is covered by a cap plate 11 which is arcuate transversely and extends the entire length of the apparatus. At intervals along the under face of 90 the cap plate 11, inturned bends 12 are provided which prevent the cap plate from sliding off the top of the shell before the concrete has been poured.

At the forward or working end of the shell, an extension band 13 is provided (see Figs. 1 and 3), which band makes the conduit a trifle larger at its end to permit ready withdrawal of the mold after the concrete

has set. This extension band is permanently secured in any desirable way upon the outside of the shell section and is split or broken at the joint between the sections, so that whether the auxiliary section 9 is employed or is removed, a slight enlargement in the passageway of the conduit will be formed at the forward end of the apparatus. The extension band 13 extends only about 10 two-thirds of the way around the shell, as seen in Fig. 3.

In the embodiment of the invention illustrated in Figs. 1 and 1^a, a construction suitable for making twenty feet of pipe is shown, 15 which employs two molds each ten feet long and joined together at their ends. Each mold has two toggles or expansion means to cause the sections of the shell to separate or close together when desired. Operating 20 means is provided at the forward end of the apparatus for causing all the toggles to work together. The two molds are shown as connected by a coupling plate 14 which is an annular member secured within two aligned 25 molds at their abutted ends. When the apparatus is shipped, the molds will be separated, but in use in the field the molds will be permanently joined together so that twenty feet of 10-inch or 12-inch conduit 30 may be laid at a time.

The size and form of the interior of the conduit is determined by that portion of the mold including the shells and the expansion means. The lower part of the conduit is 35 laid in the trench and may assume the size and form of the excavation. The outer and upper part of the conduit is shaped by a pair of side forms 15 in conjunction with a hopper member. See Figs. 3 and 4. The 40 side forms 15 are arcuate transversely and extend the length of the mold. The hopper comprises a pair of arcuate sections 16 whose curvature is that of the side forms 15 having upstanding flanges 17 and handles 18 adjoining the flanges and holding the parts 45 of the hopper together. The flanges 17 are spaced apart as best shown in Fig. 2 to provide a wide mouth for receiving the concrete as it is poured from the mixer. The 50 forward end of each side form has a raised offset 15^a, and the forward end of the hopper member has a raised offset 19, these two offset portions being arcuate transversely, as shown in Fig. 3, and providing a bell or 55 enlargement at the joint between two sections of the conduit. This bell is formed only on the upper half of the conduit, since the side forms and hopper extend for only approximately half the circumference of the 60 conduit. At the top of the offset portion 19 a slot 22 is provided for a purpose to be described.

With the present apparatus, a cloth 21 65 preferably canvas or the like is doubled and laid over the cap plate 11 extending the en-

tire length of the mold. The fold of the cloth is indicated at 21^a (Fig. 1^a). This cloth should have a width substantially equal to one-third of the circumference of the shell or drum, and when properly positioned 70 has its forward end extending to the offset 19. The purpose of using this cloth is four-fold: first, to keep the concrete from getting under the cap; second, to prevent the oil coated on the outside of the shell from 75 being swept off by the pouring of the concrete with resultant sticking of the concrete to the cap plate and drum; third, to permit rapid work with liquid or sloppy concrete, so that as soon as one section has 80 set the mold may be withdrawn and immediately used with another section; and fourth, to make a good surface on the upper part of the conduit on the inside thereof.

When the concrete 20 has been poured in 85 through the hopper member and has set, the shell is contracted and withdrawn, leaving the cloth sticking to the inside of the conduit. Because the cloth has been doubled, however, one half of it will be free from the 90 concrete and it will then be easy to take hold of the end of this free half and peel the cloth off the inside of the conduit, whereupon it may be used over again for the adjoining section of the conduit.

The means for expanding and contracting the shell sections will now be described. Each mold has a pull rod 23 located axially of the shells. Where two molds are joined together, as in making 20 ft. of pipe, the 100 two pull rods 23 will be coupled by means of a sleeve 24 of any convenient form so that the toggles in each mold will act simultaneously. The forward end of the pull rod 23 is screw-threaded as indicated at 25 to receive a nut 26 in turn pivotally connected with a pull strap 27. The other end of the pull strap 27 has an angularly-bent end 32 (Fig. 1) connected by a bolt or the like 33 with an operating wheel 30. This operating wheel turns upon an axis 29 mounted between a pair of brackets 28 secured in any desirable way to the inside of the shell. The operating wheel 30 is provided with a plurality of holes 34 in a circular series. The wheel also carries spokes 31 on its periphery so shaped as to be readily received within one end of a turning tool 40. The element 33 is passed through a selected one of the 110 holes 34 in the wheel.

At suitable intervals along the pull rod 23 toggle means are provided for connecting the rod with the inside of the shell so that longitudinal movement of the rod is translated into expansion or contraction of the shell. Each toggle includes a pair of set collars 35 secured upon the pull rod. Between each pair of set collars a number of blocks 36 are held. Each block 36 has a squared end and a rounded end and is so 120 125 130

mounted that it may turn about the pull rod 23 as an axis. A pair of straps 37 is secured to the sides of each block 36, each pair of straps comprising a toggle arm. The 5 outer arms of the straps 37 approach each other and are joined with an angle piece 39 mounted upon the inside of the shell at a convenient point. Preferably there are four toggle arms for a mold making conduits as 10 large as ten or twelve inches. For small molds as few as two arms may be employed and with very large molds the number of arms will be increased as desired.

When the auxiliary section 9 is employed 15 one of the blocks 36^a is joined to a pair of diverging legs 38 each connected with the joined flanges 8, 10, as shown in Fig. 4. If the same apparatus is used for building a smaller conduit the legs 38 will be disconnected or even removed from the apparatus.

For this smaller pipe, each block 36 will be turned about the rod 23 or put into the reverse position as illustrated in Fig. 5 and connected with the toggle arms in this position. 20 Thus, the effective length of each toggle arm is decreased, whereby the expansion and contraction of the apparatus is changed to correspond with the decreased size of conduit to be made.

30 The drawing illustrates the toggle arms as being disposed at right angles to the pull rod, in which position the shell is expanded to its utmost extent. When the parts are in this position, the pull strap has its bent 35 end 32 pressing against the axis 29 of the pull wheel. If, however, it is desired to release the mold from the conduit so as to withdraw the same preparatory to building another section, the operator will place a tool 40 over one of the spokes 31 and will pull downward on the tool to cause the wheel to rotate in a clockwise direction as viewed in Fig. 1. This will first cause the pull rod to move to the left; then as the wheel is turned 45 further the rod is moved to the right and the pull strap being connected to the wheel follows the same around until the toggles are in releasing position, when the shell sections contract. The inturned flanges 7 will now 50 nearly meet each other without, however, pinching the bends 12 or preventing the ready removal of the cap plate 11. In turning the pull wheel, it is desirable to have as much room as possible in which to work 55 with the lever arm 40. For this reason, the offset section of the hopper 19 is cut away as at 22. This cut-away section or slot 22 permits the turning tool 40 to be introduced from above and then moved downwardly until it strikes the bottom of the trench. When 60 the limit of movement of the lever arm is reached, a pin will be inserted within that hole 33 nearest the appropriate edge of bracket 28 so that turning back of the wheel 65 will not be permitted while the operator gets

a new hold with his lever arm. The provision of the nut 26 on the screw-threaded section 25 of the pull rod and also the connection between the pull strap and the pull wheel enables the operator to adjust the parts 70 so that the maximum expansion of the shell may be made.

By properly using the apparatus of the present invention, I have found it feasible with a 20-foot mold to lay four sections of 75 pipe in a working day; that is, to build eighty feet of concrete pipe twelve inches in diameter or greater during eight hours. The use of a cloth as described is largely instrumental in bringing about this rapid 80 operation.

It will be noted that the pull strap 27 locks the expansion means in approximately the position of maximum expansion, as indicated in Fig. 1, because of the engagement of end 85 32 with the pivot 29. Hence it is not necessary to use pins passing through the holes 34 to lock the pull wheel when the toggles have spread the shell completely. It will also be noted that the bell or enlargement strengthens 90 the conduit where the inner passage thereof is enlarged by the extension band 13 and where conduit sections join each other. The brackets 28 are shown as secured to the removable section 9. They may be fixed 95 upon the shells 6, to the flanges 10, or at other convenient points, when the section 9 is not used.

What is claimed is:—

1. Apparatus for molding a continuous 100 concrete conduit in a trench comprising an expansible shell, said shell being composed of a plurality of arcuate sections separated at the top to permit expansion and contraction, an arcuate cap plate extending the length 105 of the shell and covering the space between the shell sections, and a flexible covering for the cap plate to prevent the concrete from sticking thereto.

2. Apparatus for molding a continuous 110 concrete conduit in a trench comprising an expansible shell, said shell being composed of a plurality of arcuate sections separated at the top to permit expansion and contraction, an arcuate cap plate extending the length 115 of the shell and covering the space between the shell sections, and a textile covering placed upon the upper side of the shell and completely covering the cap plate and extending the entire length of the shell, said covering being doubled to present two thicknesses between the concrete and shell.

3. Apparatus for molding a continuous 120 concrete conduit in a trench comprising an 125 expansible shell, means within the shell for expanding or contracting the same, and an extension band secured to the forward end of the shell on the outside thereof, said band extending along the sides and bottom of the shell but not along the top, said extension 130

band enlarging the passage of the conduit whereby ready withdrawal of the shell after the concrete has set is made possible.

4. Apparatus for molding a continuous concrete conduit in a trench comprising an expansible shell, means within the shell for expanding or contracting the same, an extension band secured to the forward end of the shell on the outside thereof, said band 10 extending along the sides and bottom of the shell but not along the top, said extension band enlarging the passage of the conduit whereby ready withdrawal of the shell after the concrete has set is made possible, and 15 means for forming the upper part of the conduit in cooperation with said shell, said means providing an enlargement or bell in the conduit at the forward end of the shell extending around the top and sides of the 20 conduit.

5. Apparatus for molding a continuous concrete conduit in a trench comprising an expansible shell, means for expanding and contracting the shell operable at one end 25 thereof, a hopper member arcuate transversely and having an offset at the working end of the shell, and side forms arcuate transversely and also offset, the offsets forming a bell or enlargement about half 30 way around the conduit on the upper and outer portion thereof at the end of every section molded by the apparatus.

6. Apparatus for molding a continuous concrete conduit in a trench comprising an 35 expansible shell, said shell being composed of a plurality of arcuate sections joined together except at the top and there separated, inturned flanges on each shell section bordering the space where the sections are separated, a cap plate curved transversely to fit upon the top of the shell and cover said 40 space, inturned bends provided on the under sides of the cap plate and extending into the space between the flanges to hold the cap 45 plate on the shell.

7. Apparatus for molding a continuous concrete conduit in a trench comprising an expansible shell, said shell being composed of a plurality of arcuate sections joined together except at the top and there separated, inturned flanges on each shell section bordering the space where the sections are separated, a cap plate curved transversely to fit 50 upon the top of the shell and cover said space, inturned bends provided on the under sides of the cap plate and extending into the space between the flanges to hold the cap plate on the shell, and means for covering the joints between the cap plate and shell 55 whereby concrete is prevented from getting in between these two parts.

8. Apparatus for molding a continuous concrete conduit in a trench comprising an 60 expansible shell, and means for expanding and contracting said shell, said means com-

prising a pull rod extending axially of the shell, a plurality of toggle arms secured against longitudinal movement on the pull rod and extending substantially radially of the shell in planes progressively spaced 70 along the pull rod, and fixed at their outer ends to the inside of the shell, and means for moving the pull rod, said means being self-locking when the shell is expanded to approximately its maximum. 75

9. Apparatus for molding a continuous concrete conduit in a trench comprising an expansible shell, and means for expanding and contracting said shell, said means comprising a pull rod extending axially of the shell, a plurality of toggle arms secured against longitudinal movement on the pull rod and extending substantially radially of the shell and fixed at their outer ends to 80 the inside of the shell, means for moving the pull rod, said means being self-locking when the shell is expanded to approximately its maximum, and means for positively locking the pull rod moving means whereby the shell may be maintained intermediate the 85 expanded and contracted states. 90

10. Apparatus for molding a continuous concrete conduit in a trench comprising a circular expansible shell, means for varying the circumferential dimensions of the shell 95 to provide a substantially circular shell of a decreased diameter, and means for expanding and contracting the shell whatever its circumference may be, said means comprising a pull rod, a plurality of toggle arms in sets, each set being fixed against longitudinal movement on the pull rod and also fixed on the shell, and separate means whereby the effective operating length of the toggle arms may be decreased to conform to 100 the changed diameter of the circular shell. 105

11. Apparatus for molding a continuous concrete conduit in a trench comprising an expansible shell, and means for expanding and contracting the shell, said means comprising a pull rod, a plurality of toggle arms fixed to the shell and pull rod in planes progressively spaced along said rod, a pull strap adjustably secured to one end 110 of the pull rod, and a wheel adjustably connected to the pull strap for reciprocating the rod. 115

12. Apparatus for molding a continuous concrete conduit in a trench comprising an expansible shell, and means for expanding and contracting the shell, said means comprising a pull rod, a plurality of toggle arms fixed to the shell and pull rod, a pull strap adjustably secured to one end of the pull rod, and a wheel adjustably connected to the pull strap for reciprocating the rod, said wheel having a plurality of spokes projecting from its rim adapted to be engaged by the end of a lever arm. 120 125

13. Apparatus for molding a continuous 130

concrete conduit in a trench comprising an expansible shell, and means for expanding and contracting the shell, said means comprising a pull rod, a plurality of toggle arms fixed to the shell and pull rod, a pull strap secured to one end of the pull rod, said pull strap having a bent end remote from the connection with the pull rod, and a wheel connected to the pull strap for reciprocating the rod, said wheel having a pivot against which the bent end of the pull strap engages to lock the parts when the shell has been expanded.

14. Apparatus for molding a continuous concrete conduit in a trench comprising an expansible shell, a hopper member having an offset at one end, a slot or cutaway portion in the offset end, and means for expanding and contracting the shell, said means comprising a pull rod, a plurality of toggle arms fixed to the shell and pull rod, a pull strap secured to one end of the pull rod, and a wheel connected to the pull strap for reciprocating the rod, said wheel having a plurality of spokes projecting from its rim adapted to be engaged by the end of a lever arm, said slot permitting movement of the lever arm up to a vertical position.

15. Apparatus for molding a continuous concrete conduit in a trench comprising an expansible shell, a pull rod extending longitudinally and axially of the shell, a plurality of toggle arms fixed at their outer ends to the inside wall of the shell, blocks connecting the toggle arms at their inner ends to the pull rod, said toggle arms being arranged in sets, collars on the pull rod holding the blocks of each set against movement along the pull rod, each block being turnable and slideable on the pull rod and being eccentrically mounted thereon, whereby the blocks when reversed with respect to their arms shorten the effective length of said arms.

16. Apparatus for molding a continuous concrete conduit in a trench comprising a circular expansion shell, said shell being composed of a plurality of arcuate sections, one of said sections being removable to reduce the circumference of the shell and produce a circular shell of less diameter, and

means for causing expansion and contraction of the shell irrespective of the presence or absence of the removable shell section.

17. Apparatus for molding a continuous concrete conduit in a trench comprising a circular expansion shell, said shell being composed of a plurality of arcuate sections, one of said sections being removable to reduce the circumference of the shell and provide a circular shell of less diameter, means for causing expansion and contraction of the shell irrespective of the presence or absence of the removable shell section, said means comprising a rod extending longitudinally of the shell, and a plurality of toggle arms connected to the rod and shell and supporting the rod in the longitudinal axis of the shell.

18. Apparatus for molding a continuous concrete conduit in a trench comprising an expansible shell, and means for expanding and contracting the shell, said means comprising a pull rod, a plurality of toggle arms fixed to the shell and pull rod, a pull strap adjustably secured to one end of the pull rod, and a wheel adjustably connected to the pull strap for reciprocating the rod, a bracket secured to the shell and supporting the wheel, the wheel having a plurality of holes arranged in a circle for receiving the connecting element of the pull strap and for receiving pins to act as stops when the shell is being expanded.

19. Apparatus for molding continuous concrete conduits in a trench comprising a circular expansible shell, means for varying the circumferential dimensions of the shell to provide a circular shell of a different diameter, means comprising a pull rod, and a plurality of toggle arms in sets adapted to expand and contract the shell, and a reversible means for pivoting the toggles on the pull rod, said means when in reversed position adapted to change the pivotal point of the toggles whereby the effective length of the toggle arms may be varied to conform to the changing diameter of the circular shell.

In testimony that I claim the foregoing as my own, I have hereto affixed my signature.

THOMAS DE LA MARE.
